US00D749569S

(12) **United States Design Patent**
Ji et al.

(10) **Patent No.:** **US D749,569 S**
(45) **Date of Patent:** **** Feb. 16, 2016**

(54) **MOBILE PHONE**

(71) Applicant: **LG Electronics Inc.**, Seoul (KR)

(72) Inventors: **Seunghyun Ji**, Seoul (KR); **Hyunwoo Yoo**, Seoul (KR)

(73) Assignee: **LG Electronics Inc.**, Seoul (KR)

(**) Term: **14 Years**

(21) Appl. No.: **29/497,061**

(22) Filed: **Jul. 21, 2014**

(30) **Foreign Application Priority Data**

Jan. 22, 2014 (KR) 30-2014-0003506

(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof where the right side view is a mirror image;

FIG. 5 is a top plan view thereof; and,

FIG. 6 is a bottom plan view thereof.

The broken lines depict parts of the mobile phone that form no part of the claimed design.

1 Claim, 5 Drawing Sheets
